UNITED STATES PATENT OFFICE.

NATHAN M. BUMPUS, OF CURTICE, OHIO.

CHAIN PROPELLER FOR BOATS.

1,187,810.

Specification of Letters Patent. Patented June 20, 1916.

Application filed September 2, 1915. Serial No. 48,672.

To all whom it may concern:

Be it known that I, NATHAN M. BUMPUS, citizen of the United States, residing at Curtice, in the county of Ottawa and State 5 of Ohio, have invented certain new and useful Improvements in Chain Propellers for Boats, of which the following is a specification.

My invention relates to new and useful 10 improvements in ships and more particularly to ships embodying continuous chain propellers, the primary object of my invention being the provision of a ship's hull having a raceway extending longitudinally and 15 centrally of the bottom of the ship for the endless chain propeller so constructed that the blades of the propeller do not enter the water until they have reached their lowermost point of movement and are, therefore, 20 vertical.

A further object of my invention consists 25 in providing sprocket wheels of such size, and a propeller chain having links of such lengths, that the blades will be inclined at an angle, when leaving the water, until they have passed above the water level and will, therefore, not raise any water into the raceway through which the blades move.

In this connection, a still further object 30 of my invention consists in providing means for permitting escape of water from the raceway should any be raised into it as might occur when the boat was backing.

A still further object of my invention consists 35 in providing longitudinal guides along the sides of the raceway to support the upper and lower stretches of the propeller chain and insure proper movement of the chain and blades.

With these and other objects in view, my 40 invention will be more fully described, illustrated in the accompanying drawings, and then specifically pointed out in the claim which is attached to and forms a part of this 45 application.

In the drawings: Figure 1 is a side elevation 50 of a ship hull constructed in accordance with my invention, parts being broken away to disclose the raceway and propeller mechanism; Fig. 2 is a front elevation of the ship with part of the bow broken away to disclose the propeller mechanism which is shown in transverse vertical section; Fig. 3 is a fragmentary perspective view of a portion 55 of the propeller chain and of the guides along which it travels; Fig. 4 is a view cor-

responding to Fig. 1, showing a slightly modified form of drive mechanism construction, particularly for boats having a deep draft.

Corresponding and like parts are referred to in the following description and indicated in all the views of the drawings by the same reference characters.

In the embodiment of my invention, as 65 illustrated in the drawings, 10 indicates the hull of the vessel which may be of any usual or preferred type, with the exception of such modifications as are necessary for the type of driving mechanism which I employ. As best shown in Figs. 1 and 2 of the drawings, the bottom of the hull is provided with a centrally and vertically disposed, longitudinally extending raceway 11 terminating at its ends adjacent the bow 70 and stern of the hull. Near the lower portion of this raceway, the sides of the hull are connected by a hollow partition 12 terminating at its ends in slightly spaced relation to the ends of the raceway and providing 75 a substantially rectangular chamber 13 communicating at its sides with the interior of the ship hull itself and therefore capable of receiving merchandise, whereby 80 the carrying capacity of the vessel is not 85 unduly diminished. This wall or partition may be interiorly braced, as shown at 14, if deemed advisable. As clearly shown in Fig. 1, the ends of the raceway and the ends 90 of the partition are reversely curved in order to provide substantially circular spaces to receive the sprockets or driving drums of the power mechanism. The raceway includes these spaces, a channel 15 formed in the bottom of the boat, and a passageway 95 16 above the partition 12 and communicating 100 at its ends with the spaces 17, these spaces having previously been pointed out. The bottom of the hull, at the bow, is provided with a rearwardly directed extension 18 spaced below the true bottom of the boat 105 and extending rearwardly to a point somewhat behind the forward end of the partition 12, being closed at its bottom and sides but open at its rear end and forming in effect a continuation of the circular space or chamber 17 at the forward end of the vessel.

A drive shaft 19, journaled in suitable bearings 20 mounted within the hull of the vessel and at opposite sides of the raceway 11, extends transversely of the circular space 110 17 at the rear end of the raceway and sub-

stantially centrally thereof. Power from any suitable source may be transmitted to this drive shaft by a belt 21 passed about a pulley 22 upon one end of the shaft or by means 5 of a train of gearing, a pitman rod and crank arm or any other equivalent mechanism, as preferred. Within the raceway this drive shaft carries spaced sprocket wheels 23 of equal diameter and having the 10 same number of teeth correspondingly arranged. A similar shaft 24 is correspondingly mounted in the forward circular space 17 and within the raceway is provided with spaced sprocket wheels 25 identical in construction and size with the sprocket wheels 15 23. These latter sprocket wheels may, however, be loosely mounted to turn upon the shaft 24 and the latter fixed in its bearings or may be keyed upon the shaft and the 20 shaft journaled to rotate in its bearings.

Trained about the sprocket wheels 23 and 25, is the endless drive chain, indicated as a whole by the numeral 26, the upper and lower stretches of which run in the passage 25 16 and channel 15, respectively, of the raceway 11. This chain propeller or driving chain includes parallel series of links 27 connected by pivot shafts 28, the shafts being passed through overlapping ends of the 30 links of one series and through corresponding overlapping ends of corresponding links of the other series, whereby the links are pivotally connected to form an endless chain. The ends of the shafts extend beyond the outer faces of the links 27 and the channel 15 and passageway 16 are provided at either side with longitudinally extending guideways 29 U-shaped in cross section to form guide channels to receive the ends of 35 the shafts. The links 27 are so spaced as to engage against the outer faces of the sprocket wheels 23 and 25 and are held against outward movement toward the ends of the shafts 28 by collars 30 or other suitable 40 means. It will of course be appreciated that these links are of such length that the teeth of the sprocket wheels will successively engage successive shafts of the chain in such a manner that driving of the sprocket wheels 45 23 will cause a continuous movement of the chain about the front and rear sprocket wheels. Preferably, these links are relatively long and the sprocket wheels are provided with correspondingly few teeth, the 50 wheels shown in the drawings each having four teeth to engage the shafts 28 of the chain, in the manner shown. This chain carries a plurality of transversely extending propeller blades 31, each of which is provided at its inner edge with spaced collars 32 for attachment to the shafts 28. Preferably, these propeller blades are secured to alternate shafts, as clearly indicated in the drawings, in such a manner that when the 55 section of chain carrying them is in a hori-

zontal position, the blades extend vertically. Braces 33 are connected by eyes 34 to the central outer portions of the rear faces of the blades and at their opposite ends are formed with sleeves 35 which surround the 70 intermediate portions of adjacent shafts 28. It will, therefore, be seen that these propeller blades are held against any angular movement relative to the links connecting the shaft upon which the blade is mounted 75 and the shaft to which its brace is connected. These blades extend substantially the full width of the raceway 11 and are of such length as to just clear the outer walls of such raceway when the chain is in movement. It will of course be understood that their inner edges at the ends are cut-away, as shown at 36 to clear the links and guides 29.

From the foregoing description, the operation of my improved endless chain propeller will be readily understood. Assuming that power is applied to the shaft 19 to turn it in a counterclockwise direction, looking at it from the direction in which it is 85 shown in Fig. 1, the upper stretch of the chain will be moved forwardly through the 90 passage 16, while the lower stretch of the chain will be moved rearwardly through the channel 15, its blades 31 projecting below 95 the bottom of the vessel and into the water. This forcing of these blades through the water will, of course, due to the resistance of the water, force the vessel ahead. It should be noted that by providing the extension 18, the blades in passing about the 100 sprocket wheels 25 will reach a vertical position before they meet the water as the successive passage of the blades through the extended portion 18 will prevent entrance of 105 water into such portion. Of course, if the boat is being driven backward, the movement of the chain about the sprockets will be reversed and water will be drawn in through the extension 18. This water can, 110 however, escape back through the circular chamber at the forward end of the boat and will not, therefore, flow through the passage 16. It should be further noted at this 115 point, that the chain links are so proportioned with respect to the side of the sprockets, over which they operate, that the propeller blades, as they pass upwardly through the circular space 17 at the rear of the boat, will pass above the water line before they 120 reach a horizontal position and will not, therefore, draw water into the passage 16.

In Fig. 4 of the drawings, I have illustrated a construction which is identical with that previously described with but one exception. This construction is intended for use with vessels having a relatively deep draft and merely consists in enlarging the end chambers 37 which correspond to the chambers 17 in order that idler rollers 38 125

may be positioned below the sprockets 23 and 25 to properly bring the lower stretch of the chain below the bottom of the boat and still permit the drive chain 19 to be sufficiently elevated in the boat for convenient application of power. As the increasing in size of these chambers and the provision of the rollers, which are idly mounted upon shafts 39 are the only changes in construction, no further description of this form is necessary. It might be well to note, however, that the parts shown in this figure, where they correspond with the form shown in the previous figures are given the same reference numerals.

Although I have illustrated and described my invention with considerable detail, it will of course be understood that the propeller chain may be made in many different ways and power transmitted to the chain in many different ways. For this reason I do not wish to be limited to such details but reserve the right to make various minor

changes, within the scope of the appended claim, without in the slightest degree departing from the spirit of my invention.

Having thus described the invention, what is claimed as new is:

In ship construction, a hull formed with a longitudinal raceway opening through its bottom, sprocket wheels at the front and rear ends of the raceway, means for imparting power to one of the sprocket wheels, an endless chain trained about the sprocket wheels and carrying propeller blades, and means for keeping water from the blades as they pass about the forward sprocket wheel until they have assumed a vertical position, said means including a rearward extension formed upon the bottom forward portion of the hull and projecting horizontally throughout its length, opening at a point at the rear of the forward sprocket wheel.

In testimony whereof I affix my signature.

NATHAN M. BUMPUS. [L. S.]
